EBENEZER SEAVER, OF BOSTON, MASSACHUSETTS.

Letters Patent No. 77,540, dated May 5, 1868.

IMPROVED CLOTHES-PIN.

The Schedule referred to in these Letters Patent and making part of the same.

Be it known that I, EBENEZER SEAVER, of Boston, in the county of Suffolk, and State of Massachusetts, have invented a new and improved device for retaining clothes or other fabrics upon a line, which I term a Double-Fast Clothes-Pin; and I do declare that the following is a full, clear, and exact description of the same, reference being had to the accompanying drawings, making a part of this specification, in which—

Figure 1 represents a perspective view of my finished clothes-pin.

Figure 2, another of the same in section, as it appears previous to being fastened together; and

Figure 3 a clothes-pin long known, and at the present time in common use.

Many ingeniously-constructed clothes-pins have been made, intended to secure fabrics upon a line with greater certainty than is realized with or by the old-style pin represented at fig. 3. That there is need of a more reliable clothes-holding device is indicated by repeated attempts at improvement thereon by means of springs, hinges, levers, &c., but, as said old-style pin is generally admitted to be all that can be desired, except in its liability to split, and to be worked from a line by the wind, and as proposed substitutes heretofore offered are equally subject to accidental removal, it follows, that no substantial advance in the right direction has yet been attained.

The frequent failure of the said old-style pin to remain on a line is principally due to the fact that it can bring but one fastening-capacity (that of an easily-displaced friction-grasp of the legs) to bear upon a garment to keep it in place; and as the aforesaid substitutes, whether differing more or less in form of construction or principle of action, are also made to depend wholly upon a single mode of retention, they are consequently unsuccessful in like manner.

Referring to the drawings, fig. 1, A A', B B', C C' represent the pin as finished in duplicate parts, and securely fastened together by rivets or otherwise. That portion marked A B is the head or solid end of the pin. A' B' (being the parts between C C' and the head) are the legs, obliquely converging towards the head, so as to form a gradually-tapering "line-space," which, as the pin is thrust downward, will, in some part of its length, be narrow enough to meet and press against the sides of a garment, holding it with a force that may be termed a "friction-grasp." Near the entering end of the line-space are clamping-projections or teeth C C', as shown, which are, by elastic pressure, kept in forcible contact with each other at their points, by the act of fastening together the head-portions A and B, the uniting surfaces of which are bevelled, (as shown in fig. 2,) expressly to produce such result at and upon the said teeth C C'.

The points of contact of teeth C C' are reached by a gentle slope in both directions, that is to say, from the ends of the legs and from the widest part of the line-space, to permit the line, &c., to be entered and withdrawn with little friction. The "line-space slope," however, is purposely made less inclined, in order to guard against any unintentional displacement of the pin from a line.

Almost any close-grained wood will be suitable to the manufacture of my clothes-pins, but they may also be made of any natural or artificial material, if possessed of sufficient elasticity, and unobjectionable in other respects.

In general contour, the "head" and a part of the "line-space" of my device may be described as resembling the old-style pin, (fig. 3;) yet, unlike that pin, mine cannot split, and will, with increased power, resist other ordinary sources of displacement; still further unlike it, the legs of mine are armed with teeth pressed forcibly together, placed near the open end of the pin.

I am aware that clothes-pins have been heretofore made with teeth or protuberances, but their object seems to be simply to form, by their upper sides, the walls of a recess for the line.

The novelty of my invention mainly consists in the bevel given to the inner surfaces of the head-portions A and B. These surfaces are first brought temporarily together by any convenient means, then permanently secured in immediate contact, (say by rivets.) This act of riveting the head also has the effect to draw the other inner parts of the pin towards each other, pressing into close contact the points of teeth C C' with elastic force. The pressure exerted at points C C' has two results. That which for the sake of distinction I will call the first

(and minor) result of said pressure, is that it tends to keep a pin in exact position as placed on a line, by operating as an incidental support to the friction-grasp fastening of the legs above; in other words, the friction-grasp of the legs and the pressure-grasp of the teeth are mutual auxiliaries. The second (and principal) result attained by this pressure is that it compels the points of teeth C C' to impinge upon a fabric, and forcibly hold the same. In brief, the said induced action at and of the points C C' aids one fastening, and forms by itself another.

Having thus described my invention, I make no claim to so much of it as may be similar to the old-style pin, either as to its form or operation; but

What I do claim, and desire to secure by Letters Patent, is—

The bevelled contact-surfaces of the parts A and B, as shown at fig. 2, in combination with the teeth C C', as and for the purpose specified.

In testimony whereof, I have signed my name to this specification in the presence of two subscribing witnesses.

EBENEZER SEAVER.
